(57) CLAIM

The ornamental design for cigarette package, as shown and described.

DESCRIPTION

FIG. 1 is a front left top perspective view of a cigarette package, showing our new design, with the lid closed;

FIG. 2 is a front view thereof;

FIG. 3 is a left view thereof;

FIG. 4 is a right side view thereof;

FIG. 5 is a top side view thereof; and,

FIG. 6 is a front view thereof with the lid opened.

The broken line portion of the figure drawings is included to show unclaimed subject matter only and forms no part of the claimed design.
